(57) **CLAIM**

The ornamental design for a surgical gas diffuser, as shown and described.

DESCRIPTION

FIG. 1 is a front, bottom and left side perspective view of a surgical gas diffuser, which embodies our design.

FIG. 2 is a rear, top and right side perspective view thereof.

FIG. 3 is a front view thereof.

FIG. 4 is a rear view thereof.

FIG. 5 is a bottom view thereof.

FIG. 6 is a top view thereof.

FIG. 7 is a left side view thereof; and,

FIG. 8 is a right side view thereof.

The broken lines in the drawings illustrate portions of the surgical gas diffuser, which form no part of the claimed design.

The surgical gas diffuser illustrated in FIGS. 1-8 includes symbolic breaks, and any portion of the surgical gas diffuser between the break lines forms no part of the claimed design.
